UNITED STATES PATENT OFFICE.

HUGO ROBERTS FERNANDEZ, OF HABANA, CUBA.

THERMOSTATIC SWITCH.

Application filed October 7, 1924. Serial No. 742,214.

To all whom it may concern:

Be it known that I, HUGO ROBERTS FERNANDEZ, a citizen of Cuba, and a resident of Habana, Cuba, have invented a new and 5 Improved Thermostatic Switch, of which the following is a full, clear, and exact description.

This invention relates to thermostatic switches and more particularly to an electrically controlled circuit breaker which may be utilized as a flasher or for any other purpose desired wherein a circuit is to be automatically opened and closed.

A further object is to provide an expandable frame in which a twisted flexible device supports a circuit breaker and is caused to move to open and closed position at an expansion and contraction of its support.

With these and other objects in view, the invention consists in novel features of construction and combinations and arrangements of parts which will be more fully hereinafter described and pointed out in the claims.

In the accompanying drawings—

Figure 1 is a perspective view of my improved device;

Figure 2 is a view in section on the line 30 2—2 of Figure 1, illustrating in addition, more or less diagrammatically, a circuit including a pair of lamps;

Figure 3 is a view similar to Figure 2 but illustrating a circuit closer in open position.

1, 1 represent a pair of hollow perforated, and preferably corrugated columns which are preferably of zinc or any other suitable metal which will readily expand and contract. These columns are connected at their 35 ends by crossbars 2 and 3, and are insulated from said crossbars by means of blocks 4. Hooks 5 may be connected to the upper bar 2 and function as supports, or the device 40 may be supported in any other desired manner and in any position desired.

In the upper and lower bars 2 and 3 adjusting bolts 6 and 7 are located preferably at the centers of these bars and are provided with nuts 8 to secure them in any desired 45 position of adjustment. A cord, wire or other flexible connecting member 9 is secured in any approved manner to the bolts 6 and 7, and, adjacent said bolts 6 and 7, member 9 is twisted and is under a predetermined normal tension.

This member 9 has its separate runs ex-

panded at its intermediate portion and is secured to and supports a plate 10. On this plate 10 a contact 11 is secured and is normally held against a screw contact 12 carried by an arm 13 fixed to one of the columns 1. A coil 14 connects contact 11 with the other column 1. Normally, the tendency of the member 9 to turn in one direction will hold the contact 11 against contact 12, but when the columns 1 expand longitudinally and a pull is had on the member 9 this member 9 will cause the plate 10 to turn and carry the contact 11 away from contact 12.

To illustrate a practical use of my improved device I show in Figure 2 a line wire 15 connected in circuit with any suitable source of electricity and also connected with a pair of lamps 16 and 17. Branch wires 18 and 19 connect the wire 15 at opposite sides of the lamp 16 with the columns 1 so that the lamp 16 is in a shunt circuit. It is to be understood that the current is only sufficient to illuminate one of the lamps and hence the current will take the course of least resistance, namely, through the wire 18, column 1, coil 14, plate 10, contacts 11, 12, arm 13, and the other column 1, thence through the wire 19 and the lamp 17, bringing this lamp 17 to incandescence.

As the temperature of the columns 1 rises, due to the passage of the electric current or due to any other cause of heat, the bars 2 and 3 will be moved in a direction away from each other causing the plate 10 to turn slightly, separating the contact 11 from the contact 12. This will then cause the current to pass directly through the lamp 16 and illuminate this lamp while the other lamp 17 will glow or be entirely extinguished. As the temperature of the columns 1 decreases, which decrease is relatively rapid because the columns are hollow and circulation of air is permitted throughout, the contact 11 will move against the contact 12 and the circuit will be as before.

Various slight changes and alterations might be made in the general form of the parts described without departing from my invention, and hence I do not limit myself to the precise details set forth but consider myself at liberty to make such slight changes and alterations as fairly fall within the spirit and scope of the appended claims.

I claim:

1. A thermostatic switch, comprising a thermostatic expandable frame, a double run

twisted flexible member secured in the frame, a circuit breaker carried by the flexible member and to which turning movement is imparted by the flexible member, **5** means connecting the circuit breaker with a fixed contact, and said circuit breaker adapted to engage a second contact.

2. A thermostatic switch, comprising a thermostatic expandible frame, a double run **10** twisted flexible member secured in the frame, a circuit breaker carried by the flexible member and to which turning movement is imparted, means connecting the circuit breaker with a fixed contact and said circuit breaker **15** adapted to engage a second contact, and a pair of parallel insulated members carrying the respective contacts and constitut-

ing parts of said thermostatic expandible frame.

3. A device of the character described, **20** comprising a pair of parallel hollow perforated metallic columns, bars connecting the columns and insulated therefrom, an endless twisted member adjustably connected to the bars, a plate carried by the **25** flexible member and adapted to be moved thereby in accordance with the expansion and contraction of the columns, a fixed contact carried by one of the columns, a contact carried by the plate and normally engaging the fixed contact, and a coil connecting the contact of the plate with the other column.

HUGO ROBERTS FERNANDEZ.
